UNITED STATES PATENT OFFICE.

GEORGE W. KOONS, OF PHILADELPHIA, PENNSYLVANIA, ASSIGNOR TO IDA GERTRUDE KOONS, OF SAME PLACE.

DESIGN FOR A BOX.

SPECIFICATION forming part of Design No. 25,537, dated May 19, 1896.

Application filed February 11, 1896. Serial No. 578,959. Term of patent 7 years.

To all whom it may concern:

Be it known that I, GEORGE W. KOONS, a citizen of the United States, residing in the city and county of Philadelphia, State of Pennsylvania, have invented and produced a new and original Design for a Box, of which the following is a specification, reference being had to the accompanying drawing, forming part thereof.

10 The leading feature of my design for a box for candy, &c., is, first, an ornament on the lid thereof, consisting of a wad of fluffy material shaped into a body, a head, and a neck simulating a chick, and, next, the representation of a chick, an egg-shell, and nest on said lid.

The figure represents a perspective view of a box embodying my design.

In the drawing, A designates the lid of a box, and B designates the representation of a nest thereon.

C designates the representation of a chick, and D designates the representation of an egg-shell, from which the chick is apparently hatched.

25 What I claim is—

The design for a box, substantially as described and shown.

GEORGE W. KOONS.
